THREAD TREATING APPARATUS FOR SEWING MACHINES

Fred Ashworth, Wenham, Mass., assignor to
United Shoe Machinery Corporation, Paterson, N. J., a Corporation of New Jersey

Application March 13, 1931. Serial No. 522,253

12 Claims. (Cl. 91—46)

The present invention relates to shoe sewing machines, and more particularly to the thread waxing or lubricating devices of such machines.

In some classes of work, particularly in sewing outsoles to the welts of welted shoes, white or colored threads are often used in the stitching operation. In changing from a white to a colored thread or from a thread of one color to a thread of another color, it is desirable to 10 change the wax or lubricating material through which the thread passes in order to prevent soiling of the thread by the color which may be washed out of the previously used thread by the lubricating material. The pots containing 15 the wax or lubricant which have heretofore been used are not readily removable from the machine, and consequently a change in the wax or lubricant has occasioned considerable inconvenience and loss of time.

20 The principal object of the present invention is to provide a simple and efficient apparatus which can be readily applied, without appreciable loss of time, to a sewing machine for waxing or lubricating thread of any desired 25 character or color supplied to the machine. Other objects are to simplify the construction and improve the operation of coloring, waxing, lubricating or other thread treating apparatus ordinarily employed in outsole or other stitching 30 operations.

The invention will be readily understood by reference to the accompanying drawings which illustrate the invention in its preferred form, and to the following description of the construction 35 therein.

In the drawings, Figure 1 is a view in side elevation of a portion of an outsole stitching machine with thread treating apparatus embodying the invention applied thereto; Figure 2 is a 40 plan view on an enlarged scale, of said thread treating apparatus, a part having been broken away; Figure 3 is a view in side elevation of the apparatus on a similar scale; Figure 4 is a 45 plan view, in detail, of a thread supporting device employed in conjunction with the thread treating apparatus of my invention; and Figure 5 is an end elevation of the apparatus of my invention shown in cooperative relation to the 50 thread supporting device illustrated in Figure 4.

The head of a sewing machine is indicated at 55 supported on a pedestal 4 and embodies the usual stitch-forming and thread manipulating devices. While the invention may be used with other types of machines, a lockstitch sewing

head having a rotary loop taker 6 and other necessary mechanisms is illustrated.

At the rear of the supporting pedestal, in place of the ordinary wax pot heretofore employed, an aligned series of duplicate thread 60 treating receptacles may be attached to the machine by means of a dove-tail guide 10 which, for convenience of manufacture, in the construction illustrated, is formed on a bracket secured to the machine by bolts 12.

65 One or more individual receptacles for containing thread treating fluids may be mounted upon the dove-tail guide 10, proper vertical position being insured by a projecting stop 14 extending beneath the lower edge of the guide 10. 70 Each receptacle is complete in itself and may be interchangeably mounted with respect to any other.

75 Each receptacle is formed with a main supporting frame 16 having a dove-tail slot 18 on one side and a dove-tail guide 20 corresponding to that on the frame of the machine on the other side. The dove-tail guide 10 on the machine, being similar to the dove-tail slot on the receptacles, any receptacle may be interchangeably 80 slipped into position on the machine. One or more additional receptacles may be slipped over corresponding connections on those already attached to the machine, thus providing dependent and interchangeable mountings therefor. Each 85 frame 16 is provided with a stop 22 corresponding with stop 14 on the guide 10, to prevent vertical displacement of the receptacles.

Beneath each frame 16 is suspended a cage 24 90 held in place by screws 26 passing through angularly bent tabs 28 of the cage and having a threatened engagement with holes in the frame. Each frame 16 is hollow for the passage of a container 30. From the bottom of each cage one or more resilient spring members 32 extend upwardly to form a flexible support for the container. Upward thrust of these resilient members is resisted by a cover 34 overlapping the entrance to each container and adjustable vertically to insure seating and complete closure of the opening. On the upper side of the cover a suitably shaped bracket 36 is secured upon which is mounted a dry thread tension or other incoming thread directing pulley 38 and an outgoing thread directing truck 40 arranged with its axis at right angles to the incoming thread pulley. The arrangement is such that incoming thread will enter at right angles to the direction of alignment of a series of superposed receptacles while the outgoing thread leads in the direction of 105 110

alinement of such a series. In this manner, any of the outgoing threads will align themselves properly with a conveniently located thread opening 42 at the rear of the stitching head.

5 A thread supply may be conveniently located adjacent any receptacle and may be attached to the machine in any suitable manner. In the preferred form it is mounted on an integral extension of the guide 10. Extending from the 10 guide is an arm 44 on the end of which a clamp portion 46 is formed. A rod 48 sliding through the clamp supports a rotary thread supply reel 50. This reel is substantially similar to that described in the co-pending application of Erastus 15 E. Winkley, Serial No. 379,413, filed July 19, 1929, and comprises a yielding arm 52 pivotally mounted upon a radial member 54 fixed on the rod 48. Frictional control on the reel 50 is afforded by a brake 56 resting, under the tension 20 of a spring 58, upon the periphery of a wheel 60 fixed to rotate with the reel. Thread drawn from the reel extends upwardly and laterally over a horizontal portion of the arm 52. Tension on the thread tends to counteract the effect 25 of spring 58, releasing the brake 56 and permitting withdrawal of the thread. If a single thread is employed, the supply reel 50 may be moved longitudinally through movement between the rod 48 and the clamp 46 to position properly 30 the reel with relation to any of the receptacles, the thread being directed laterally over the tension arm 52, through the dry thread tension 28, and into the selected thread treating container. Other thread manipulating equipment such as a 35 stripper 62, thread truck 64, and a thread compressing device 66 may be formed in, or attached to, the cover 34. This apparatus is substantially similar to that described in my co-pending application Serial No. 372,993 filed June 22, 1929 40 to which reference may be had for a more full and complete description thereof.

The containers are readily accessible for refilling, cleaning or other adjustments and the thread manipulating equipment is readily removable therefrom by means of the arrangement for attaching the cover 34 to each receptacle. Each cover is provided with extending ears 68 and 70, having vertical holes directed therethrough. The hole in ear 68 cooperates 45 with a nipple 72 extending upwardly from a bolt 74 fixed at one end of the frame 16. From the opening in ear 70, one end of an elongated rod 76 projects downwardly through a clamp member 78 formed on the other end of each receptacle frame 16. The rod 76 may be bolted or 50 otherwise made fast to the ear 70.

Raising or removal of the cover 34 is permitted by releasing the clamp 78 from the rod 76, exposing the contents of the container 30 60 and permitting manipulation of the ordinarily enclosed parts attached to the cover. Lateral swinging movement of the cover is afforded by sufficient upward movement along the rod 76 to permit the downwardly extending parts to clear 65 the sides of the frame. The container 30 may be removed or replenished with a supply of a thread treating medium upon upward movement or removal of the cover. The parts attached to 70 the cover may be held in any desired elevated position by manipulation of the clamp 78 or the container may be fixedly secured in position within the frame and supporting cage, as illustrated in the drawings, with the cover firmly closing the opening to the container against 75 entrance to undesirable material.

The thread treating medium may be of any suitable character such as wax, a coloring compound, lubricant or cement which is either normally in the liquid form or may be reduced to a liquid within the container. By forming the 80 container 30 of glass or other transparent material and the cage 24 with cut away portions, the quantity of thread treating fluid may be readily ascertained without removal of the cover. Any one of a series of aligned superposed receptacles 85 may be selected to act upon the thread as it passes from the supply to the work with simple and convenient adjustment and without undue loss of time. Receptacles may be quickly interchanged or additional ones depended to those already in place. Such apparatus is particularly suited for use on a machine employing different colors of thread. Where certain portions of the work require one color and other portions, another color, or where a needle thread of one character and a locking thread of another character are employed, a shift from one to the other can quickly be made or, if desired, a plurality of thread reels can be permanently positioned, one in fixed relation to each receptacle. 90 95 100

Having thus described the invention, what is claimed is:

1. A thread treating apparatus for sewing machines having, in combination, a machine frame provided with a dove-tail guide, a wax receptacle, formed with a dove-tail slot on one side to fit the guide on the frame and with a dove-tail guide on the other similar to the guide on the frame whereby a plurality of similar individual receptacles may be inter-changeably 105 mounted on the machine frame or may be mounted one upon another.

2. A thread treating apparatus for sewing machines having, in combination with the machine frame, a series of duplicate aligned wax 110 receptacles, each formed with a dove-tail slot on one side and with a dove-tail guide on the other for cooperating with corresponding connections on the machine frame or on adjacent receptacles, thread guides mounted on each receptacle for directing incoming thread at right angles to the direction of alignment and outgoing thread in the direction of alignment of the series of receptacles, a thread supply device adjustably mounted to slide into adjacent cooperating 115 position with any of said receptacles, and means for directing the thread from said device at right angles to the direction of sliding movement thereof.

3. A thread treating apparatus for sewing machines having, in combination, a mounting frame, a supporting cage beneath the frame, a container slidable through the frame and into said cage, a cover for the container arranged for lateral swinging or vertical sliding movement into engagement with the upper surface of the container to maintain it in position within the cage, means mounted on the cover for guiding thread into and out of the container and a nipple 130 formed on the frame for cooperating with an opening in the cover to prevent lateral swinging of the cover while in its lowermost position.

4. A thread treating apparatus for sewing machines having, in combination, a mounting frame 145 adapted to be mounted on a sewing machine, a container supported by said frame, a rod slidable in the frame, a cover for the container carried by the rod, means mounted on the cover for guiding thread into and out of the container 150

- and means for clamping the rod in fixed position.
5. A thread treating apparatus for sewing machines having, in combination, a mounting frame adapted to be mounted on a sewing machine, a supporting cage beneath said frame, a container slidable through the frame and into said cage, a cover for the container arranged for vertical movement into engagement with the upper surface of the container to maintain it in position within the cage and means mounted on the cover for guiding thread into and out of the container. 80
10. A thread treating apparatus for sewing machines comprising a supporting frame, a fluid container, a cover for the container, and means mounted on the cover for guiding thread into and out of the container and through the fluid, said frame being provided with a guide to fit a guideway on the sewing machine frame and with a guideway similar to the guideway on the machine frame whereby a plurality of similar individual apparatus frames may be interchangeably mounted on the machine frame or may be 85 mounted one upon another. 90
15. A thread treating apparatus having, in combination, a mounting frame, a supporting cage beneath said frame, a resilient member within the cage, a container slidable through the frame and into contact with the resilient member within the cage, a cover for the container arranged for movement into engagement with the upper surface of the container to compress it against said resilient member and means mounted on the cover for guiding thread into and out of the container. 95
20. A thread treating apparatus for sewing machines having, in combination with the frame of the machine, a series of duplicate receptacles, each comprising a mounting frame formed with attachment means arranged on opposite sides for cooperating with corresponding means on the machine frame or on adjacent receptacles, a supporting cage suspended from the frame, and a container disposed within the cage. 100
25. A thread treating apparatus for sewing machines having, in combination, a mounting frame, a closed ended supporting cage suspended from the frame, a container disposed within the cage, a cover for the container having a sliding attachment to said frame, means mounted on the cover for guiding thread into and out of the container and adjustable means for positioning said cover in engagement with the container and for maintaining the container in fixed relation inside the cage. 110
30. A thread treating apparatus having, in combination, a mounting frame, a removable container projecting beneath the frame, a rod slidable vertically in the frame, a cover for the container mounted on the rod and carrying thread manipulating equipment and rod clamping means on the frame for fixedly securing the cover and container in position. 115
35. A thread treating apparatus for sewing machines comprising a supporting frame, a fluid container, a cover for the container, and means mounted on the cover for guiding thread into and out of the container and through the fluid, said frame being provided with a guide to fit a guideway on the sewing machine frame and with a guideway similar to the guideway on the machine frame whereby a plurality of similar individual apparatus frames may be interchangeably mounted on the machine frame or may be mounted one upon another, and a thread supply device movable to different positions to cooperate with different containers of said apparatus. 120
40. A thread treating apparatus for sewing machines comprising a supporting frame, a fluid container, a cover for the container, and means mounted on the cover for guiding thread into and out of the container and through the fluid, said frame being provided with a guide to fit a guideway on the sewing machine frame and with a guideway similar to the guideway on the machine frame whereby a plurality of similar individual apparatus frames may be interchangeably mounted on the machine frame or may be mounted one upon another, a thread supply device slidably mounted upon the machine frame, and means for adjustably securing said device adjacent different receptacles. 125
45. A thread treating apparatus having, in combination, a mounting frame, a removable container projecting beneath the frame, a rod slidable vertically in the frame, a cover for the container. 130
50. A thread treating apparatus having, in combination, a mounting frame, a removable container projecting beneath the frame, a rod slidable vertically in the frame, a cover for the container. 135
55. A thread treating apparatus having, in combination, a mounting frame, a removable container projecting beneath the frame, a rod slidable vertically in the frame, a cover for the container. 140
60. A thread treating apparatus having, in combination, a mounting frame, a removable container projecting beneath the frame, a rod slidable vertically in the frame, a cover for the container. 145
65. A thread treating apparatus having, in combination, a mounting frame, a removable container projecting beneath the frame, a rod slidable vertically in the frame, a cover for the container. 150

FRED ASHWORTH.
